UNITED STATES PATENT OFFICE.

BURTON P. HALL, OF FANWOOD, NEW JERSEY, AND WILLIAM GRIMSHAW, OF GLENELYN, ILLINOIS; SAID HALL ASSIGNOR TO SAID GRIMSHAW.

FIRE-EXTINGUISHER.

1,294,260.

Specification of Letters Patent. Patented Feb. 11, 1919.

Application filed November 11, 1918. Serial No. 261,988.

To all whom it may concern:

Be it known that we, BURTON P. HALL and WILLIAM GRIMSHAW, citizens of the United States, and residents, respectively, 5 of Fanwood, in the county of Union and State of New Jersey, and of Glenellyn, in the county of DuPage and State of Illinois, have invented a new and useful Improvement 10 in Fire-Extinguishers, of which the following is a specification.

This invention relates to fire extinguishers and relates particularly to improvements in automatic sprinklers and to an improved process of manufacturing the same, whereby 15 they will be subjected to desired operating stresses.

The object of the invention, as it relates to the construction of the sprinkler, is to provide an automatic sprinkler of simple 20 and relatively cheap construction and effective for its designed purpose.

As it relates to an improved process of manufacturing our improved sprinkler, the object of the invention is to provide a new 25 and novel process for subjecting the parts of the sprinkler to and maintaining them under desired operating stress, which shall be simple and effective.

To effect the foregoing objects, our improved 30 sprinkler comprises the various features and details of construction and our improved process the various steps herein-after described and claimed.

In the accompanying drawing, in which a 35 sprinkler of our invention and constructed in accordance with our improved process is fully described,

Figure 1 is a side view of said sprinkler; and

40 Fig. 2 is a sectional view of the sprinkler frame on the line 2-2 of Fig. 1.

Referring now to the drawings, A designates the frame of the sprinkler as a whole, which, as regards its usual features, and, 45 excepting as hereinafter particularly described, may be of any usual or approved construction and will be readily understood by persons familiar with the art without a detailed description thereof.

50 In accordance with our present invention, the water discharge nozzle of our improved sprinkler, instead of being formed directly in the neck 1 of the sprinkler, is formed by a bushing 2 fitted to the bore of the neck 55 1 so as to be initially movable endwise

therein, the seat for the cap 3, which closes the water discharge nozzle being formed at the inner end of said bushing 2.

As shown, the cap 3 is adapted to be secured in closed position by means of toggle 60 levers comprising articulated strut members 4 and 5, the remote ends of which, respectively, engage recessed bearings 6 and 7 formed in the cap 3 and in the inner end of a boss 8 formed integral with the side 65 arms of the sprinkler frame remote from the neck 1 thereof. Said toggle levers also comprise laterally projecting arms 9 and 10, the ends of which are connected by a fusible member designated, as a whole, 11, 70 and which may be of any desired or approved construction.

We wish it understood, however, that the particular means shown for securing the cap 3 in closed position have no necessary 75 relation to the present invention, and we do not, therefore, desire to limit ourselves thereto, as our invention contemplates the use of any desired or approved means for this purpose.

As shown, the bushing 2 is secured in the bore of the neck 1 of the sprinkler by an interlocking bead and groove 12 and 13 formed on the bushing 2 and in the bore 80 of the neck 1 of the sprinkler, respectively. 85

In accordance with our invention, as it relates to a process of assembling the parts of the sprinkler and subjecting them to a desired operating stress, the groove 13 is first formed in the bore of the neck 1, after which the bushing 2 is inserted into the bore of the neck 1 of the sprinkler frame and the various parts of the sprinkler assembled, in the usual manner, the bushing 2 is then forced inward so as to subject the parts of the 90 sprinkler to a desired operating stress. Said bushing is then expanded to form the bead 12 in position to interlock with the groove 13, and the sprinkler is then completed. 95

Any well known form of jack adapted for 100 the purpose may be used to force the bushing 2 endwise in the neck of the sprinkler frame, and any form of expanding tool adapted for the purpose—of which there are several known to the trade which may 105 quickly and conveniently be adapted for the purpose—may be used for forming the bead 12, the plunger of the jack being made hollow to permit the expanding tool to be inserted into the bore of the bushing 2. 110

We claim:

1. The process of stressing an automatic sprinkler of the type in which the water nozzle is formed by a bushing secured in the neck of the sprinkler frame, which consists in first assembling the parts of said sprinkler in operative relation with the bushing forming the nozzle of the sprinkler inserted in the neck of the sprinkler frame so as to be movable endwise therein, forcing said bushing endwise to subject the parts of the sprinkler to stress, and in then securing said bushing in position in the neck of the sprinkler corresponding to a desired stress on the parts of the sprinkler, substantially as described.
2. The process of stressing an automatic sprinkler of the type in which the water nozzle is formed by a bushing secured in the neck of the sprinkler frame, which consists in forming a groove in the neck of the sprinkler frame, assembling the parts of the sprinkler in operative relation with the bushing forming the nozzle of the sprinkler inserted in the neck of the sprinkler frame so as to be movable endwise therein, forcing said bushing endwise to subject the parts of the sprinkler to stress, and expanding said bushing in line with the groove formed in the neck of the sprinkler when said bushing is in position corresponding to a desired stress on the parts of the sprinkler, thereby forming an interlocking bead and groove on said bushing and in the neck of the sprinkler, respectively, which will secure said bushing against endwise movement in the neck of the sprinkler and will

maintain the parts of the sprinkler under desired operating stress, substantially as described.

3. A sprinkler comprising a frame provided with a tubular neck and a bushing secured therein in position to subject the parts of the sprinkler to desired operating stress and provided with a bore which forms the water nozzle of the sprinkler, substantially as described.

4. A sprinkler comprising a frame provided with a tubular neck and a bushing secured therein in position to subject the parts of the sprinkler to desired operating stress and provided with a bore which forms the water nozzle of the sprinkler, the means for securing said bushing in the neck of the sprinkler comprising an interlocking bead and groove formed on said bushing and in the neck of the sprinkler, substantially as described.

5. A sprinkler comprising a frame provided with a tubular neck, a bushing secured therein in position to subject the parts of the sprinkler to desired operating stress and provided with a bore which forms the water nozzle of the sprinkler, and an abutment for the nozzle closing means formed integral with the sprinkler frame, substantially as described.

In testimony, that we claim the foregoing as our invention, we affix our signatures this 7th day of November and 4th day of November, A. D. 1918.

BURTON P. HALL
WILLIAM GRIMSHAW.
